COMBINATION FLUID CONTAINER AND
CLOSURE HAVING A SCREW DRIVER
PROJECTION

Samuel Reider, North Arlington, N. J.

Application May 10, 1949, Serial No. 92,340

2 Claims. (Cl. 81—3.1)

1

This invention relates to container closure and more particularly to a cap removably secured over the outlet of a fluid container.

The present invention provides a cap for a fluid container which cap has a tongue-like or screw-driver blade projection extending therefrom. Such cap is of great convenience when the fluid in the container is to be passed therefrom into an aperture or opening closed by a screw. For example, the cap when positioned to close the outlet of a container of cigarette lighter fluid may be used to remove the screw plug closing the filler-opening of the lighter. Thereafter, the cap may be removed from the container and the lighter fluid poured into the lighter. The cap is then used to screw the screw plug into the filler-opening to close said opening when the lighter is filled with fluid. The cap may also be used as a closure on containers of lubricating oil or the like wherein it is useful to remove a screw from a lubricating aperture and return the screw to said aperture. The uses above-mentioned are set forth by way of example and not by way of limitation.

The invention will be understood from the following description when considered in connection with the accompanying drawing forming a part thereof and in which:

Fig. 1 is a front elevational view of one embodiment of the present invention;

Fig. 2 is a side elevational view of the embodiment of the invention illustrated in Fig. 1;

Fig. 3 is a front elevational view of another embodiment of the invention;

Fig. 4 is a side elevational view of the embodiment of the invention shown in Fig. 3;

Fig. 5 is a front elevational view of a further embodiment of the invention;

Fig. 6 is a side elevational view of the embodiment of the invention illustrated in Fig. 5, and

Fig. 7 is a side elevational view of a cigarette lighter partly broken away and disclosing the cap of the embodiment of the invention illustrated in Fig. 1 positioned to unscrew the plug from the filler opening of the lighter.

Like characters of reference refer to like parts throughout the several views.

Referring to Figs. 1 and 2 of the drawing a container 10 is a usual form of lighter fluid or oil can and has a spout 11 thereon which spout has a closure or cap 12 on the outlet end 13 thereof. The closure or cap 12 is internally threaded at 14 while spout 11 is externally threaded at 15 (Fig. 7).

Cap 12 has a knurled peripheral rim 16 around

the top 17 thereof and a screw-driver blade or tongue 18 extending diametrically transversely of the cap and projecting upwardly from rim 16. Blade 18 is preferably formed integrally with said cap.

As illustrated more particularly in Fig. 7, screw-driver blade 18 is adapted to fit into the slot 19 of a screw 20. The screw 20, as illustrated in Fig. 7, is a screw plug for a filler-opening in a lighter 21 which plug has screw-threads 22 thereon which cooperate with screw-threads 23 in the filler-opening.

In operation, blade 18 of cap 12 is placed in slot 19 of screw plug 20. Container 10 with spout 11 thereon is then turned in a direction to unscrew threads 22 on the plug from threads 23 in the filler opening thereby removing the plug from said opening. Preferably, the threads 14 in cap 12 and threads 15 on spout 11 are such that when container 10 is turned to remove plug 20 from the filler opening of the lighter that cap 12 tends to become tightened on said spout.

After plug 20 is removed from the filler opening, cap 12 is removed from spout 11 by grasping knurled rim 16 and turning the cap so that threads 14 are unscrewed from threads 15 on the spout. Lighter fluid is then poured into the lighter through the filler opening. When filling of the lighter is completed, plug 20 is replaced in the filler opening and tightened therein by placing blade 18 of cap 20 in slot 19 and turning the cap by grasping knurled rim 16. Cap 12 is thereafter replaced on spout 15 to close the outlet end 13 thereof.

While the hereinabove described operation is preferable, it will readily be understood that cap 12 may be removed from spout 11 and then used to unscrew plug 20 from the filler opening.

In the embodiment of the invention shown in Figs. 3 and 4, cap 12 is circular and has a top 24 with a depending skirt 25 which skirt is screw-threaded at 26 to engage screw-threads 27 on the neck of a bottle 28. A screw-driver blade 29, which may be integrally formed with the top of said cap, projects downwardly from the inner side of top 24 to a point beyond the lowermost part of skirt 25.

Cap 12, in operation, is removed from the neck of bottle 28 and used to loosen or tighten screws by placing blade 29 in the screw slot and turning cap 12 in the desired direction.

In the embodiment of the invention disclosed in Figs. 5 and 6, cap 12 is similar to that illustrated in Figs. 3 and 4 except that screw-driver blade 29 extends outwardly of top 24. Cap 12

and blade 29, in the embodiment of the invention shown in Figs. 5 and 6, may be used in tightening or loosening screws in the same manner as in the embodiment of the invention shown in Figs. 1 and 2, as hereinbefore described.

Inasmuch as various modifications may be made in the forms of the invention herein disclosed and in the location and relative arrangement of the several parts of said invention without departing from the principles thereof, it will be understood that the invention is not to be limited excepting by the scope of the appended claims.

What is claimed is:

1. In combination with a liquid container for inflammable liquid for a lighter having a liquid containing compartment with a screw-threaded liquid inlet normally closed by a screw-threaded plug, the threads of said inlet and plug engaging one another, said container being of such size and shape as to be readily retained in the hand of a user and having a spout secured on and projecting outwardly from one end thereof and from which spout liquid passes from the container, the outlet end of the spout being screw-threaded, a closure removably secured on said outlet end of the spout, the closure having screw-threads adapted to cooperate with said screw-threads of the spout, and a screw-driver projection on the closure and extending outwardly thereof, said screw-threads of the spout and the closure being opposite to said screw-threads of said lighter inlet and the lighter plug and so arranged that the closure becomes tightened on the spout when said screw-driver projection is used to loosen the plug from said compartment inlet whereby said container is usable as a screw-driver on the outlet end of the spout, the spout acting as the shank of said screw-driver and the closure as the blade thereof to remove said plug from the lighter compartment inlet.

2. In combination with a liquid container for

inflammable liquid for a lighter having a liquid containing compartment with a screw-threaded liquid inlet normally closed by a screw-threaded plug, the threads of said inlet and plug engaging one another, said container being of such size and shape as to be readily retained in the hand of a user and having a spout secured on and projecting outwardly from one end thereof and from which spout liquid passes from the container, the outlet end of the spout being screw-threaded, a closure removably secured on said outlet end of the spout, the closure having screw-threads adapted to cooperate with said screw-threads of the spout, and a screw-driver blade projection formed integrally with the top of said closure and extending transversely and outwardly thereof, said screw-threads of the spout and the closure being opposite to said screw-threads of said lighter inlet and the lighter plug and so arranged that the closure becomes tightened on the spout when said screw-driver projection is used to loosen the plug from said compartment inlet whereby said container is usable as a screw-driver on the outlet end of the spout, the spout acting as the shank of said screw-driver and the closure as the blade thereof to remove said plug from the lighter compartment inlet.

SAMUEL REIDER.
